(57) **CLAIM**

The ornamental design for a mobile telephone, as shown and described.

DESCRIPTION

FIG. 1 is a front view of a mobile telephone in a closed position showing my design;

FIG. 2 is a rear view thereof;

FIG. 3 is a perspective view thereof;

FIG. 4 is a right side view thereof;

FIG. 5 is a left side view thereof;

FIG. 6 is a top view thereof;

FIG. 7 is a bottom view thereof;

FIG. 8 is a front view of the mobile telephone of FIG. 1 in an open position;

FIG. 9 is a rear view thereof;

FIG. 10 is a perspective view thereof;

FIG. 11 is a right side view thereof;

FIG. 12 is a left side view thereof;

FIG. 13 is a top view thereof;

FIG. 14 is a bottom view thereof;

FIG. 15 is a rear view of a second embodiment of the mobile telephone in a closed position wherein the only differences compared to the first embodiment are the additional concentric circles and text at the top center; and,

FIG. 16 is a rear view of the second embodiment of the mobile telephone in the open position.
